Inventor

Frank H. Zuch,

By his Attorney D. Garfield & Co.

UNITED STATES PATENT OFFICE.

FRANK H. ZUCH, OF RICHMOND HILL, NEW YORK

AIR-HEATER FOR FURNACES.

1,148,812.

Specification of Letters Patent. Patented Aug. 3, 1915.

Application filed February 13, 1915. Serial No. 6,491.

To all whom it may concern:

Be it known that I, FRANK H. ZUCH, a citizen of the United States, and residing at Richmond Hill, Long Island, in the county of Queens and State of New York, have invented certain new and useful Improvements in Air-Heaters for Furnaces, of which the following is a specification, such as will enable those skilled in the art to which it appertains to make and use the same.

This invention relates to means for heating air supplied to furnaces of various kinds and classes for the purpose of improving the operation of the furnace and providing for a more perfect combustion, and the consequent saving of fuel; and the object thereof is to provide a device or apparatus of this class which is simple in construction, effective in operation and may be easily applied to a furnace or heating apparatus of almost any class.

The invention is fully disclosed in the following specification, of which the accompanying drawing forms a part, in which the separate parts of my improvement are designated by suitable reference characters, said drawing being a sectional view showing my improved furnace air heating device applied to an ordinary furnace.

In the drawing forming part of this specification, I have shown a part of a furnace, comprising a front wall *a*, one side wall *b*, and the grate *c*, and the front wall *a* is provided with the usual door opening *a*² and with a door *d* which, in the form of construction shown, is of the ordinary crown shape and which is hinged to the front wall *a* of the furnace and adapted to open outwardly in the usual manner but the hinges are not shown in the drawing.

In the practice of my invention, I connect with the door *d*, a box or casing *e* which extends a predetermined distance into the furnace when the door is closed, and which is adapted to swing through the door opening *a*² when the door *d* is opened or closed, and the dimensions of which will depend upon the dimensions, size or character of the furnace.

In the form of construction shown, the casing *e* is composed of a top member *e*¹, a bottom member *e*³ and side plates *e*⁴, and these separate parts may be cast or formed in any desired manner, and when said parts are connected they form a complete box or casing of which the top and side members

*e*² and *e*³ are provided with ears *e*⁵ through which are passed screws, pins, or bolts *e*⁶ by which the box or casing *e* is secured to the door *d*.

The top member *e*¹ and bottom member *e*³, in the construction shown, consist of vertically convoluted plates forming in connection with the top member downwardly directed portions *e*⁷ and in connection with the bottom member upwardly directed portions *e*⁸, and this divides the box or casing *e* into separate vertically arranged air spaces or passages *f* which are placed in communication alternately at the top and bottom thereof.

The front downwardly directed part *e*⁷ of the top portion *e*¹ of the casing *e* forms the outer wall of the front air space or passage *f*, and in the bottom thereof are air inlet ports *g*, while the inner upwardly directed part *e*⁸ of the bottom portion *e*³ of the casing forms the inner wall thereof, and is provided in the top portion thereof with air discharge ports *g*² through which air passing through the box or casing *e* is discharged into the furnace.

The form and construction of the box or casing *e* adjacent to the door *d* provides therein, as shown, a supplemental air chamber or passage *f*² and the door *d* is provided with the usual air register device *d*² through which air passes into said supplemental chamber or passage *f*².

The side walls of the vertically arranged chambers or passages *f* are provided with alternately arranged baffle plates *h*, and these baffle plates may be formed in connection with, or attached to the walls of the chambers or passages *f* in any desired manner, and air admitted through the door *d* follows the course of the arrows *a* and after being highly heated is discharged into the furnace over the grate or over the coal or other fuel material placed on the grate, and this air produces a more thorough and complete combustion and a consequent saving of fuel, and also operates to prevent, to an extent, the discharge of heavy black smoke from the furnace chimney or flue.

With this construction it will be seen that there is a continuous vertical and inward flow of air from the time it enters or passes through the door until it is discharged into the furnace, and with my improvement there is a much greater heating surface than would be possible with other devices of this

class as the vertical spaces e^o in the top and bottom of the casing e and which open upwardly and downwardly and laterally through the side walls a^4 of the said casing 5 increase the heating surface or surfaces, the hot gases of combustion in the furnace being free to circulate through the spaces e^o and around all the surface walls of the box or casing e and between the separate compartments thereof.

Having fully described my invention, what I claim as new and desire to secure by Letters Patent, is:—

15 An air heating device adapted to be connected with the inner side of the door of a furnace and to swing inwardly and outwardly therewith, said device comprising a box or casing composed of a top, bottom and

side walls, the top and bottom being provided with deep transverse convolutions 20 forming deep transverse recesses which open upwardly and downwardly, and laterally through the side walls, and which divide said box or casing into vertically and transversely arranged air spaces or passages 25 which alternately communicate at the top and bottom thereof.

In testimony that I claim the foregoing as my invention I have signed my name in presence of the subscribing witnesses this 30 11th day of February 1915.

FRANK H. ZUCH.
